UNITED STATES PATENT OFFICE.

VAINO NIEMELA, OF CLEVELAND, OHIO.

TOOL-HOLDER.

1,235,364.

Specification of Letters Patent. Patented July 31, 1917.

Application filed November 6, 1915. Serial No. 59,984.

To all whom it may concern:

Be it known that I, VAINO NIEMELA, a citizen of the United States, residing at Cleveland, in the county of Cuyahoga and State of Ohio, have invented certain new and useful Improvements in Tool-Holders, of which the following is a specification.

My present invention relates to improvements in lathe tool holders, and more particularly to a tool holder adapted to receive bits of varying cross sections.

The object of my invention is to provide a tool holder that may be adjusted to any angle and which will resiliently retain the tool in proper engagement with the work.

A further object of my invention is to provide a tool holder that will be readily adapted to the tool post of an ordinary lathe.

20 A still further object of my present invention is to provide a device of improved construction giving greater elasticity to the bit and still holding the tool with relation to the carriage.

25 Having these and other objects of general utility and design in view, I have illustrated an operative construction of my invention in the accompanying drawings, in which:—

Figure 1 is an elevational view of my tool holder.

Fig. 2 is a top plan thereof.

Fig. 3 is a front elevation of the device as shown in Fig. 1.

Fig. 4 is a fragmental detail of the forward end of my resilient arm connecting the bit post to the tool holder.

No. 5 is sectional detail taken on line 5—5 of Fig. 1.

Fig. 6 is a perspective view of the special bolt and bearing as shown in Fig. 5.

Fig. 7 is a detail of a modified form of the bit post shown accommodating a larger bit or tool, other than shown in Fig. 1.

Fig. 8 is a section taken on line 8—8 of Fig. 7; and—

Fig. 9 is a perspective view of the special form of bolt employed in the assembling of my modified bit post, as shown in Figs. 7 and 8.

50 Similar reference characters refer to similar parts throughout the several views.

My improved lathe tool holder comprises the usual shank 10, adapted to be inserted into the tool post of the lathe (not shown).

55 Secured to the forward end of the shank 10,

by means of a split collar 11, is a substantially inverted U-shaped spring member 12, provided at its opposite end with a recessed bearing post 13. Rotatably secured to the bearing 13, I provide a suitable bit post, 60 comprising a split collar 14, (Fig. 1) frictionally secured to the bearing 13, by means of a lateral bolt 15, adapted to pass transversely therethrough; said bolt is provided with an enlarged head 15^a and has a 65 transverse slot 15^b therethrough. Passing through the slot 15^b, and lying adjacent a groove 14^a, in the vertical side of the bit post, is a bit 16.

In Figs. 7 and 8, I have shown a modified 70 form of bit post, wherein in place of the centrally disposed bolt 15, I provide two screws 17—17 one on either side of the recess or groove wherein fits the bit or tool; one-half of the heads of said bolt are mortised out, as in Fig. 9, for the purpose of 75 accommodating the bit shank as shown.

As described, my tool holder is a suitable holder for tools of different styles, such as form tools, backing off tools, boring tools, 80 threading tools, and tools having different sized shanks, and made of different sizes and shapes of tool stock. The goose-neck 12, as provided and described, facilitates the use of the various tools inasmuch as they may 85 be used safely and to great advantage wherein the speed of operation is greater than normal, without danger to the operator or to the tool.

It will further be apparent that I have 90 provided a tool holder with a double or triple adjustment, whereby the tool may be adjusted to any suitable angle necessary to perform its duties.

Having thus described my invention, it 95 will be obvious to others skilled in the art to which it appertains, that numerous modifications and refinements may be made therein, and still come within the scope of my appended claim.

100 What is claimed is:—

A tool holder including a shank member; an inverted U-shaped resilient member, a split-collar connecting one end of said U-shaped member with one end of said shank, 105 a bearing post having an annular concave-bottomed recess, said bearing post being carried at the opposite end of said U-shaped member, a bit post comprising a split collar frictionally secured to said bearing post, a 110

lateral bolt adapted to pass transversely through said collar, said bolt itself having a slot, said bit post having a groove opposed to said slot, said slot receiving the bit, said bit lying adjacent to said groove in the bit post.

In testimony that I claim the foregoing as

my own I have hereto affixed my signature in the presence of two subscribing witnesses.

VAINO NIEMELA.
